UNITED STATES PATENT OFFICE

ROBERT J. BURROWS, OF BUCHANAN, MICHIGAN, ASSIGNOR TO CLARK TRUCKTRACTOR COMPANY, OF BUCHANAN, MICHIGAN, A CORPORATION OF MICHIGAN

MUFFLER FOR INTERNAL COMBUSTION ENGINES

Application filed April 13, 1927. Serial No. 183,339.

My present invention has to do with mufflers through which the exhaust gases from an internal combustion engine are discharged, for the purpose of silencing the exhaust and also cooling the exhaust gases. As is commonly known, when a mixture of gasoline and air is exploded, the carbon of the gasoline unites with the oxygen of the air, forming carbon dioxide and carbon monoxide, while the hydrogen of the gasoline combines with the oxygen of the air to form water. In the ordinary muffler installation the water formed is evaporated by the heat, and the gas comes out at a high temperature, in many cases incandescent particles of carbon being discharged through the muffler, which is highly objectionable, particularly because of the increased fire hazard due to the danger that fires may be caused by sparks from the motor exhaust.

In recent years the use of small internal combustion motor operated tractors has become quite extensive in and around manufacturing establishments, warehouses etc., but the possible fire hazard due to their use is regarded by many as a serious objection, and has retarded the sale of such tractors to a considerable extent. To avoid that objection by eliminating any danger of fire due to the discharge of sparks from the exhaust, and also to provide improved means for muffling the noise of the exhaust, and delivering the exhaust gases at a low temperature, are the objects of my present invention. I accomplish these objects as illustrated in the drawings and as hereinafter described. What I regard as new is set forth in the claims.

In the accompanying drawings I have illustrated my improvements as applied to a shop tractor of well known design, but it should be understood that they may be applied to other forms of internal combustion motor operated vehicles, and that the claims hereinafter made are not intended to be limited to the incorporation of such improvements in any particular style of vehicle, since they may be applied in various ways other than that shown.

In the drawings Figure 1 is a side elevation of a shop tractor, part of the hood being

broken away to expose the parts that exemplify my invention.

Fig. 2 is a partial vertical cross section on line 2—2 of Figure 1, some parts of the silencer being shown in elevation.

Fig. 3 is a vertical section on line 3—3 of Fig. 2, and

Fig. 4 is a partial horizontal section on line 4—4 of Fig. 2.

My invention essentially involves the provision of a condensing and silencing element located in the air blast from the usual cooling fan of an internal combustion motor, the parts being so designed and arranged that the exhaust gases pass from the motor to the silencer and are caused to follow a circuitous route therethrough, meanwhile being exposed to the cooling effect of such blast, with the result that the hot gases are cooled, and the moisture contained in the gas is condensed, filling the muffler and tail pipe with heavy moisture at a comparatively low temperature, part of which accumulates in the tail pipe as liquid before being ultimately discharged through the outlet. This moisture serves to quench any sparks that may be carried toward the point of discharge by the outflowing gases, eliminating all fire hazard, so that the vehicle may be used in and about warehouses and shops with entire safety. The noise of the exhaust is, of course, silenced by the passage of the gases through the condensing element.

Referring now to the drawings for a description in detail of the specific embodiment of my invention shown therein,—5 indicates the frame of the truck or tractor, and 6, 7 the front and rear wheels thereof. Mounted on the frame is an internal combustion motor 8, of any suitable type, with which is associated a radiator 9, and a fan 10 arranged to be rotated by the motor in any suitable way. In the illustrated construction, the fan is mounted on a shaft 11, and the radiator is located at the rear of the vehicle, but it is to be understood that this particular arrangement is chosen for illustration only and that these parts may be placed in other relative positions, if and when desired. As is well understood, rotation of the fan creates a cur-

rent of air that is drawn in through the radiator and flows through the space enclosed by the usual hood, which in the present instance is shown at 12.

5 At the opposite end of the machine from the radiator 9, in this instance its front end, is a vertically disposed bumper plate 13 which forms a part of the housing for the power plant, its lower end being secured to 10 the frame 5 while its upper portion connects with the adjacent end of the hood 12. This bumper plate is provided with a series of holes 14, best shown in Figs. 3 and 4, to permit air to pass therethrough, so that the air 15 current created by the fan 10, flows along through the hooded space and passes out through the openings 14.

In the hooded space, and adjacent to the inner face of the plate 13, opposite the holes 20 14, is a silencing and condensing element 15, which is preferably similar in design to an ordinary heat radiator such as are used in dwellings. The silencer illustrated is composed of a number of similar hollow units or 25 sections 16, adapted to be connected together in series to form a circuitous duct with air spaces between contiguous sections. This arrangement will be best understood from Fig. 2, in which 17 indicates longitudinal passages 30 formed in the interior of the several sections; 18 indicates laterally projecting bosses at opposite sides of the end portions of each of said sections, said bosses being provided with connecting passages 19; 20 indicates laterally 35 projecting bosses at the ends of said sections, disposed opposite the bosses 18, but not provided with connecting passages; and 21 indicates external air spaces between adjoining units, formed by the abutment against each 40 other of the bosses 18 and 20 of adjoining sections. The several sections are tightly connected together by longitudinal bolts 22, 23 that extend through the several bosses 18, 20 as usual. It will be understood, of course, 45 that the several sections are so assembled that the connecting passages 19 of adjoining sections aline so that fluid entering through one of the end sections follows a circuitous course, flowing in one direction 50 through one section and in the opposite direction through the next section, and so on, until it is discharged at the opposite end of the radiator. One of the end sections is provided with an inlet head 24 secured thereto by the bolt 23, and the opposite end section is provided with an outlet head 25 secured thereto by the bolt 22. The radiator is preferably mounted on the plate 13 by bolts 26 secured to said plate and passing through certain of the air spaces 21, their inner ends carrying plates 27 that overlap two adjoining radiator sections. Nuts 28 screwed on the bolts 26 tightly clamp the plates 27 against the radiator and hold it firmly in position.

65 The inlet head 24 is connected by a pipe 29

with the exhaust manifold of the engine 8, as shown in Figure 1, and the discharge head 25 has connected to it an exhaust or tail pipe 30 which preferably extends to the rear of the vehicle, as indicated, principally by dotted lines, in Figure 1. The general trend of said tail pipe is downward, as indicated, but preferably adjacent its rear ends it is bent slightly upward to provide a trap portion 31 in which a small amount of water can accumulate.

70 The part 32 shown in Figure 1, is the usual pipe leading from the water jacket of the motor to the radiator, the part 33 indicates a belt for driving the fan shaft 11, and the part 34 indicates one of the usual rear wheel mud 80 guards or fenders.

75 From the foregoing description it will be evident that when the motor is in operation the exhaust gases coming from the engine will pass through pipe 29 to the inlet end of the 85 silencer, will follow a circuitous course through the several sections thereof, and will be discharged through the tail pipe 30. When the motor is in operation the fan 10 is driven, which causes a flow of air through the radiator 9 into the hooded space and out through the openings 14, after passing through the spaces 21 of the silencer. This 90 flow of air around the silencer sections has a cooling effect on the exhaust gases, which are 95 thereby cooled so that the moisture carried by them is condensed.

100 The cooled gases pass out through the pipe 30, as does also the condensed moisture, the latter accumulating in the trap portion 31 of the tail pipe until it rises to a high enough level to flow out at the rear end thereof. The condensation of the moisture fills the muffler and discharge pipe with heavy vapor at a 105 comparatively low temperature, some of which assumes liquid form, which extinguishes any sparks or incandescent particles of carbon that might be on their way through the silencer, so that the discharge contains no 110 live sparks. The noise of the exhaust is muffled by diverting the direction of flow of the 115 gases, which in the device illustrated is changed twenty-two times, the gases being meanwhile cooled by the dissipation of the heat effected by the subjection of the silencer to the direct blast of cooling air from the fan.

120 The terms "front" and "rear", as herein used, are employed in a relative sense merely, since as has been indicated, so far as my invention generically considered is concerned, it is not essential that the radiator be placed at the rear of the vehicle and the silencer at the front thereof, it being important only that the silencer be exposed to the cooling influence of the current of air induced by the fan.

125 What I claim as my invention and desire to secure by Letters Patent, is—

1. In a structure including an internal combustion engine, an enclosing hood for the engine, a radiator in operative association 130

with said hood and adapted to be connected to said internal combustion engine, and a fan driven by said engine and adapted to draw air into said hood through the radiator, the combination of a muffler disposed within said enclosing hood and in the path of said air, whereby it is cooled and vapors in the exhaust gases passing therethrough are condensed, means connecting one side of the muffler with 5 said engine, and common means for discharging said exhaust gases and said condensed vapors from the muffler.

10 2. In a structure including an internal combustion engine, an enclosing hood for the engine, a radiator in operative association with said hood and adapted to be connected to said internal combustion engine, and a fan driven by said engine and adapted to draw air into said hood through the radiator, the combination of a muffler comprising a number of 15 serially connected and spaced apart sections disposed within said enclosing hood and across the blast of air moved by the fan, whereby it is cooled and vapors in the exhaust 20 gases passing therethrough are condensed, means connecting the upper portion of the muffler with said engine, and common means for discharging said exhaust gases and said 25 condensed vapors from the muffler.

30 3. In a structure including an internal combustion engine, an enclosing hood for the engine and having air holes therein, a radiator in operative association with said hood and adapted to be connected to said internal 35 combustion engine, and a fan driven by said engine and adapted to direct air through said holes and the radiator, the combination of a muffler comprising a substantially flat core disposed adjacent said air holes and in the 40 path of the air forced therethrough by the fan, whereby it is cooled and vapors in the exhaust gases passing therethrough are condensed, means connecting one side of the muffler with said engine, and common means for 45 discharging said exhaust gases and said condensed vapors from the muffler.

ROBERT J. BURROWS.
